UNITED STATES PATENT OFFICE.

WILLIAM A. HEALY, OF DETROIT, MICHIGAN, ASSIGNOR TO STANDARD TUBE & MANUFACTURING COMPANY, OF DETROIT, MICHIGAN, A CORPORATION OF MICHIGAN.

AUTOMOBILE HEATER AND MUFFLER.

Application filed February 1, 1926. Serial No. 85,173.

This invention relates to combined mufflers and heaters for automobile bodies. It has been customary heretofore in the practical art to heat automobile bodies largely with a by-pass of the exhaust in which a coil of the by-pass is located under a register. These heaters, as is very well known, have been very unsatisfactory as most of them do not provide any appreciable heat except when the motor is traveling at a speed not permitted in city driving. This is especially true in the better class of cars, with powerful motors that do not heat up except when driven at a relatively high speed. One of the chief reasons for this difficulty is that adequate circulating air is not provided to abstract the heat from the exhaust pipe.

It is the object of the present invention to overcome this difficulty by employing a forced draft and bringing the air into intimate contact with the exhaust gases, and then conducting and discharging the same into the body of the car. This method of heating is not broadly new. My invention resides in combining the heating and muffling operations in one device and so arranging the conduits that a most efficient air heating and muffling operation is secured.

I appreciate that it is also not broadly new to combine in one instrumentality a muffler and heater, and I do not broadly claim this; but I do believe that it is new to provide a shell having a battery of tubes substantially in the exhaust line, and in which the exhaust passes on the outside of the tubes where it can be muffled with suitable baffles, and a forced draft of air passes through the interior of the tubes whereby the air is completely surrounded by the hot exhaust gases so as to get the maximum heating effects for the air, while the exhaust gases are cooled by transference of heat to the air so that the exhaust gases are contracted as regards their volume in the absence of the heater, while at the same time the gases are muffled.

This arrangement completely eliminates the necessity of a separate muffler and gets a higher heating efficiency than any heater with which I am familiar.

In the drawings:

Figs. 1 and 2 are sectional views of different forms.

Figs. 3 and 4 are sections taken on the lines 3-3 of Fig. 1 and 4-4 of Fig. 2.

55 a designates the manifold; b the exhaust

pipe which leads into the tubular arm c on one side of the shell d of the combined heater and muffler. A second tubular arm e at the opposite end permits the attachment of the rear end f of the exhaust line.

This shell d includes a pair of header plates h which support a battery of tubes i in boiler fashion. This type of heater is not broadly new, but in those heaters of the elongated type that are exhibited by the prior art, it has been customary to introduce the exhaust at the ends of the heater and pass it through the tubes in the same way as done with the products of combustion in the flue type of boiler. However, I propose to build my heater on the principle which has a general analogy to water tube boilers. The fluid to which the heat is transferred is passed through the tubes. This has many of the advantages which are claimed for the water tube type of boiler, but in connection with a heater used on internal combustion engines it has several unexpected advantages which are not suggested by the water tube boiler. One of them is that it permits the use of the exterior chamber for exhaust gases. This is a spacious chamber, and hence the problems of back pressure, which have been serious ones in connection with heaters, are almost entirely eliminated.

This back pressure, as is well known, is a serious thing in automobile engines, and special designs of heaters have been proposed to introduce the exhaust gases into the tubes to eliminate as far as possible this back pressure. However, one of the most important features of introducing the exhaust gases on the outside of the tubes is that it permits the baffling of the exhaust gases and dividing the shell into longitudinal sections or chambers which can be each properly proportioned with respect to the other chambers so as to get the necessary muffling action. The placing of these baffles or partitions can be varied to vary the size of the chamber, and to get just the proper muffling action for any design of engine. This is an impossibility when the exhaust passes through the tubes, hence in all these heaters where the exhausts pass through the center tubes the usual muffler is required; consequently a double expense is incident to the use of the heater. Furthermore, I find that the exposure of the exhaust gases to the cold air about the large drum cools the

gases and retards expansion, thereby lessening the noises incident to the expansion of exhaust gases. This cooling, coupled with the expansion chambers completes the muffling action.

The baffles are designated *j* and are preferably staggered. It will be noted that they are preferably arranged so that the chambers gradually decrease in size from the forward end to the rear end as is shown in Fig. 4. This is done in two ways, or may be done in one. The baffles are caused to project further out in the shell and they are arranged closer to each other.

15 Two different forms of the construction are shown. In the form shown in Fig. 1, four headers are employed; a battery of tubes is used not only to carry the air endwise through the shell, but one header chamber *x* is used to reverse the air which comes back through other of the tubes to the header chamber *y*, from which it is discharged to the point of use. The muffler construction is just the same. This form of construction has advantages in that one current of air is subjected to heating effects through a longer path of travel. The same effect is procured in the construction shown in Fig. 2, but here the header chambers at the rear 20 end of the muffler are done away with and the return of the air being heated is effected by the elbows *z*. The baffles *r* take the place of the headers in supporting the tubes. This construction has the advantages of that 25 shown in Fig. 1, and has the added advantage that the exhaust can be discharged directly out of the end of the shell or drum.

What I claim is:

1. A combined heater and muffler for 40 automobiles or other vehicles driven by an internal combustion engine, which comprises a shell for location in the exhaust line and having ports in its walls for passage of the exhaust gases therethrough, this shell being 45 provided with a battery of tubes arranged to twice conduct air to be heated through the shell and also with baffle plates, the arrangement of the tubes and the plates being such as to provide a plurality of 50 expanding chambers which afford muffling action without causing back pressure, means for introducing air into the tubes to be heated by the exhaust gases as the gases are expanding in said chambers, and means for 55 conducting heated air to the place where it is to be utilized.

2. A combined heater and muffler for 60 automobiles or other vehicles driven by an internal combustion engine, which comprises a shell for location in the exhaust line, a battery of tubes supported in the shell arranged in two sets with the sets of tubes connected at one end, means for introducing air to one set of tubes, means for conducting 65 the air away from the other set of tubes,

means for conveying the heated air to the place where the heat is to be utilized, means for introducing the exhaust gases around the battery of tubes and discharging it from said shell, and a plurality of partial partitions across said shell through which said tubes pass for dividing said shell into a plurality of muffling chambers, the whole construction being such as to provide adequate muffling action and effect heating of the air without causing back pressure of the exhaust gases.

3. A device for the purpose specified, comprising an elongated shell provided at its front end with a header chamber, means for introducing air into said header chamber, a battery of tubes supported in said shell spaced from each other and spaced from the shell, and arranged in connection with the shell to convey the air longitudinally of the shell and then return it back to the forward end of the shell, means for affording a second header chamber at the forward end of the shell for collecting such returned air, means for conveying such heated air to the point of usage, means for introducing exhaust gases into the interior of the shell and around said tubes, and means for discharging the exhaust gases from such shell.

4. A device for the purpose specified, comprising an elongated shell provided at its forward end with two headers spaced from each other and from the forward end of the shell forming two header chambers, a battery of tubes supported by said headers and contained within the shell for taking air entering the first header chamber, transmitting it longitudinally of such shell and returning it to the second header chamber, and means for conveying the heated air from the second header chamber to the point of usage, means for introducing exhaust gases into the interior of the shell and around said tubes, and means for discharging the exhaust gases from such shell.

5. In a device of the character described, the combination of an elongated shell provided with a pair of transverse header plates spaced from each other and from the forward end of the shell, forming two header chambers, a plurality of partial partitions or baffles spaced along the shell, a battery of tubes supported in said shell spaced from each other and from the shell and arranged to take air from the first header chamber, convey it lengthwise the shell and return it to the second header chamber at the forward end of the shell, means for introducing exhaust gases around the tubes and to the interior of the shell, and means for discharging them from the opposite end of the chamber in which they are contained and about the tubes.

6. A combined heater and muffler for 130 automobiles or other vehicles driven by an

internal combustion engine, which comprises a shell for location in the exhaust line, two sets of tubes with one end of one set communicating with one end of the other set supported in the shell, means at one end for introducing air to the several tubes for twice conveying the air through the shell, means for conveying the heated air to the place where the heat is to be utilized, means for

introducing the exhaust gases around both 10 sets of tubes and discharging it from said shell, and means for dividing the shell exterior of said tubes into a plurality of connecting chambers to effect muffling.

In testimony whereof I have affixed my 15 signature.

WILLIAM A. HEALY.
